CLAIM

The ornamental design for a door latch handle, as shown and described.

DESCRIPTION

FIG. 1 is a perspective view of a door latch handle showing my new design;

FIG. 2 is a side view of the door latch handle illustrated in FIG. 1;

FIG. 3 is a top view of the door latch handle illustrated in FIG. 1;

FIG. 4 is a bottom view of the door latch handle illustrated in FIG. 1;

FIG. 5 is a front view of the exterior door latch handle illustrated in FIG. 1; and,

FIG. 6 is a front view of the interior door latch handle illustrated in FIG. 1.

The broken lines showing of door panel and handle portion are for illustrative purpose only and form no part of the claimed design.
